UNITED STATES PATENT OFFICE

166,174

CHECK STAND OR SIMILAR ARTICLE

Wayland H. Crawford, San Gabriel, Calif., assignor to Modern Village Stores, Inc.

Application November 3, 1951, Serial No. 17,275

Term of patent 14 years

(Cl. D80—2)

To all whom it may concern:

Be it known that I, Wayland H. Crawford, a citizen of the United States of America, residing at San Gabriel, California, in the county of Los Angeles and the State of California, have invented a new, original, and ornamental Design for a Check Stand or Similar Article, of which the following is a specification, reference being had to the accompanying drawing, forming part thereof.

Fig. 1 is a rear perspective view of a check stand or similar article, showing my new design; and

Fig. 2 is a front perspective view thereof.

I claim:

The ornamental design for a check stand or similar article, as shown.

WAYLAND H. CRAWFORD.
